ABSTRACT

A hydraulic control valve is provided which can amplify the pilot flow controlled a pilot valve coupled to the control valve. Orifices are inserted into the pilot and main flows so that the pressure difference or drop across these orifices may be transmitted across a spool in order to control the main flow in proportion to the pilot flow which in turn is controlled by the pilot valve.

HYDRAULIC CONTROL VALVE

BACKGROUND OF THE INVENTION:

The present invention relates to hydraulic control valves used in hydraulic driving systems, and more particularly to hydraulic control valves adapted for accomplishing various functions by controlling the large-capacity main flow as a function of small-capacity pilot flow.

In general, in hydraulic control valves which are used in hydraulic driving systems for controlling the flow rate, pressure or direction of a large flow of liquid under pressure, the whole hydraulic flow circulating in the system is made to pass an orifice. To detect the pressure difference or drop so as to control the main flow, sequence valves are used which serve to pass the hydraulic flow into a desired hydraulic circuit. Therefore the orifices and sequence valves must be made of increased size as the quantity of the control flow is increased so that a large external force is required for adjusting the gain or the like. Thus the adjustment of the control valves becomes difficult. Furthermore it becomes almost impossible to control the large quantity of hydraulic flow because of its inertia. When large-sized orifices and sequence valves are used, the control valves also become inevitably large in size and heavy in weight, thus requiring a large installation space in the hydraulic system and resulting in high system cost.

To overcome the above problems there has been devised and demonstrated a hydraulic control system in which the main flow, that is a flow of liquid under pressure in large quantity, is controlled in response to a pilot flow flowing from a small-capacity pilot valve, but this system still has some defects. One of the major defects is that while the control valve may be used to control the flow rate, the direction of the hydraulic flow and the flow rate as well as the unloading which may be considered as a sort of pressure control, a single control valve cannot accomplish various functions such as flow control, pressure control and directional control. Therefore, depending upon the requirements of a hydraulic system, various control valves each capable of accomplishing a particular function must be designed and fabricated, so that the control valves cannot be standardized and multi-purpose control valves cannot be provided. Furthermore, there is another defect in that the control valve which may function as a main relief valve or as a main-relief-unloading valve, becomes complex in construction and large in size. Moreover, in the conventional control valves of the type which may function not only as a main relief valve or as a main-relief-unloading valve but also a carry-over valve, when the pilot relief valve is opened as the actuator in the first group reaches the end of stroke or when the actuator is overloaded, the liquid under pressure is all relieved through the main relief valve to the reservoir and no carry-over is effected unless the switching valve is returned to its neutral position. Therefore the liquid under pressure which has been returned to the reservoir, results in a temperature rise which adversely affects the operation of the hydraulic system. Furthermore, when the switching valve is returned to its neutral position when carry-over to the second group is not necessary, the carry-over to the second group is effected in practice, thus resulting in a power loss and temperature rise in the hydraulic system.

There has therefore long been a need for a control valve which may accomplish flow rate control, pressure control or directional control, or combinations thereof, and furthermore may function not only as a main relief

5 valve or a main-relief-unloading valve but also as a carry-over valve without causing any power loss and temperature rise of the liquid under pressure, because of the control valve of the type described may be readily standardized.

10 Furthermore, when a control valve is provided which may accomplish the various functions of a number of different standardized pilot valves mounted on the control valve as found in the recently developed pump unit, the piping may be much simplified, maintenance and repair may be considerably facilitated, various hydraulic circuit modules may be readily provided, and the standardization of the control valves may be enhanced.

20 SUMMARY OF THE INVENTION

One of the objects of the present invention is therefore to provide a novel hydraulic control valve which can control the main flow in response to a pilot flow from one of various pilot valves mounted on or hydraulically coupled to the control valve, the pilot valves including flow rate control valves such as a throttle valve, a volumetric flow control valve and so on, pressure control valves such as a relief valve, a sequence valve and so on, load check valves and flow directional control valves.

25 Another object of the present invention is to provide a hydraulic control valve which may control the main flow in response to a pilot flow from one of the standardized pilot valves selected from the various pilot valves of the types described above and mounted on the control valve.

30 Another object of the present invention is to provide a hydraulic control valves of the type described above which may be assembled into a unitary construction so as to provide a control valve module.

35 Another object of the present invention is to provide a hydraulic control valve which may function not only as a main relief valve or main-relief-unloading valve but also as a carry-over valve.

40 Another object of the present invention is to provide a control valve which may accomplish the carry-over function in such a manner that, when a first group or one actuator in a hydraulic control system is deactivated, the liquid under pressure in the first group or actuator is carried over to a second group or actuator, and when a main-relief pilot valve is opened when the first group or actuator is activated, the liquid under pressure in the first group or actuator is also carried over to the second group or actuator.

45 Another object of the present invention is to provide a hydraulic control valve which may not only unload the liquid under pressure of a first group or actuator in a hydraulic system when a second group or actuator with or without the succeeding groups or actuators is deactivated while the first group or actuator has been kept deactivated, but may also function as a main relief valve when the pressure of the liquid in the second group or actuator with or without the succeeding groups or actuators exceeds a preset relief pressure regardless of whether the first group or actuator is activated or deactivated.

Another object of the present invention is to provide a hydraulic control valve which may detect the pressure of the liquid in a second group or actuator with or without the succeeding groups or actuators being subjected to pressure in excess of a predetermined level, so as to automatically unload the liquid under pressure in a first group or actuator of a hydraulic system.

Another object of the present invention is to provide a hydraulic control valve which may unload the liquid under pressure of a first group or actuator in a hydraulic control system when the carry-over from the first group or actuator to a second group or actuator with or without the succeeding groups or actuators is not required, but which may carry over the liquid under pressure in the first group of actuator immediately when the carry-over to the second group or actuator with or without the succeeding groups or actuators is required.

In order to attain the above and other objects of the present invention, a spool which is adapted to move or shift upwardly or downwardly depending upon the difference in pressure exerted at both ends thereof, is disposed in a valve proper, and an orifice is inserted into a pilot flow line or passage, whereas an orifice which is slightly larger in cross-sectional area than the orifice in the pilot flow line is inserted into a main flow line or passage, so that the volumetric flow in the main flow line or passage may be controlled in response to the difference between the pressure drops across the orifices in the pilot and main flow lines or passages. Therefore the hydraulic control valve of the type described may accomplish the various functions of pilot valves.

The pilot, inlet, discharge and output ports as well as other communication ports of the control valve in accordance with the present invention are positioned and spaced apart from each other according to a predetermined relation or standards, so that various standardized pilot valve may be readily mounted upon them. The control valves in accordance with the present invention may amplify the pilot flow which in turn is controlled by one of the pilot valves. A plurality of control valves in accordance with the present invention may be joined in tandem so as to provide a hydraulic control valve module.

When a suitable control valve is inserted into the pilot flow line in addition to a main relief pilot valve, the control valve in accordance with the present invention functions not only as a main-relief-unloading valve but also as a carry-over valve which will not cause any power loss and temperature rise of liquid under pressure.

The above and other objects, features and advantages of the present invention will become more apparent from the following description of some preferred embodiments thereof, taken in conjunction with the accompanying drawing.

BRIEF DESCRIPTION OF THE DRAWING:

FIG. 1 is a sectional view of a first embodiment of a control valve in accordance with the present invention;

FIG. 2 is a fragmentary view, on enlarged scale, thereof illustrating the arrangement for adjusting the cross-sectional area of an orifice inserted in a pilot flow line;

FIGS. 3A and 3B are fragmentary sectional views thereof on enlarged scale, illustrating an orifice inserted into the main flow line which may automatically

adjust its cross sectional area depending upon the direction of the main flow;

FIG. 4 is a diagram of a hydraulic circuit in which the control valve in accordance with the present invention is used as a meter-in type flow control valve;

FIG. 5 is a diagram of a hydraulic circuit in which the control valve in accordance with the present invention is used as a meter-out type flow control valve;

FIG. 6 shows a diagram of a hydraulic circuit in which the control valve in accordance with the present invention is used as a distribution and collection valve;

FIG. 7 is a diagram of a hydraulic circuit in which the control valve in accordance with the present invention is used as an overload relief valve;

FIGS. 8 and 9 show diagrams of a hydraulic circuit in which the control valve in accordance with the present invention is used as a reducing valve;

FIG. 10 is a diagram of a hydraulic circuit in which a control valve in accordance with the present invention is used as an overloading valve, when, for example, a hydraulic motor circuit is blocked by a flow-directional control valve;

FIG. 11 is a diagram of a hydraulic circuit in which the control valve in accordance with the present invention is used as a floating valve;

FIG. 12 is a diagram of a hydraulic circuit in which a control valve in accordance with the present invention is used as a three-port three-position valve;

FIG. 13 is a diagram of a hydraulic circuit in which a hydraulic control valve in accordance with the present invention is used as a four-port three-position valve;

FIG. 14 illustrates a variation thereof;

FIG. 15 is a sectional view of a control valve in accordance with the present invention which is illustrated as being used as a main-relief-unloading valve;

FIG. 16 is a hydraulic circuit diagram in which a control valve of the type shown in FIG. 15 is used as a main-relief-carry-over valve;

FIG. 17 is a diagram of a hydraulic circuit in which a control valve in accordance with the present invention is so connected as to function as a main relief valve, an unloading valve and a carry-over valve;

FIG. 18 is a diagram of a hydraulic circuit in which the control valve in accordance with the present invention is used in order to automatically unload the liquid under pressure in an actuator or the like, when the pressure of the liquid carried-over therein exceeds a predetermined level;

FIG. 19 and FIG. 20 show diagrams of hydraulic circuits in each of which the control valve in accordance with the present invention is used to carry over the liquid under pressure into an actuator or the like when, and only when, the liquid under pressure required in said actuator or the like cannot be sufficiently supplied from a hydraulic pressure source;

FIG. 21 is a sectional view of still another embodiment of a control valve in accordance with the present invention, upon which may be mounted a pilot valve or a stack of pilot valves so that the control valve may amplify the pilot flow from one of the pilot valves;

FIGS. 22 and 23 are respective top and bottom views thereof;

FIGS. 24, 25 and 26 are sectional, top and bottom views of a valve proper of the control valve shown in FIG. 21;

FIG. 27 is a sectional view taken along the line 27-27 of FIG. 24;

FIGS. 28 and 29 are sectional views taken along the respective lines 28—28 and 29—29 of FIG. 24;

FIGS. 30, 31 and 32 are respective sectional, top and bottom views of a top cover of the control valve shown in FIG. 21;

FIG. 33 is a sectional view taken along the line 33—33 of FIG. 30;

FIGS. 34, 35 and 36 are respective sectional, top and bottom views of a bottom cover of the control valve shown in FIG. 21;

FIG. 37 is a sectional view taken along the line 37—37 of FIG. 34;

FIGS. 38, 39 and 40 illustrate valve assemblies used in combination with the control valve in accordance with the present invention;

FIG. 41 is a side view of the control valve of the present invention, upon which are mounted valve assemblies and a solenoid valve;

FIGS. 42 and 43 are respective side and bottom views of two control valves joined in tandem;

FIGS. 44, 45 and 46 are respective sectional, top and bottom views of a control valve in accordance with the present invention which may function not only as a main relief valve but also as an unloading valve;

FIG. 47 is a cross-sectional view taken along the line 47—47 of FIG. 44;

FIG. 48 is a sectional view of a modification of a bottom cover of the control valve shown in FIG. 44;

FIG. 49 is a side view of the control valve shown in FIG. 21, joined in tandem to the control valve of the type shown in FIG. 44 but having the modified bottom cover as shown in FIG. 48;

FIG. 50 is a bottom view thereof;

FIG. 51 is a sectional view of a modification of the control valve shown in FIG. 44 which may further function as a carry-over valve;

FIG. 52 is a top view thereof;

FIG. 53 is a cross-sectional view taken along the line 53—53 of FIG. 51;

FIG. 54 is a sectional view of another modification of the control valve shown in FIG. 44, which may further function as a carry-over valve and which is adapted to be used with the control valve of the type shown in FIG. 21;

FIGS. 55 and 56 are sectional views taken along the lines 55—55 and 56—56 of FIG. 54, respectively;

FIGS. 57 and 58 are respective side and bottom views of a plurality of control valves in accordance with the present invention, which are joined in tandem so as to provide a bracket-type control valve system;

FIGS. 59 and 60 are respective side and bottom views of a hydraulic control valve system in which a plurality of control valves in accordance with the present invention are joined in tandem and are controlled by a multi-control valve and a linear control valve;

FIGS. 61 and 62 are respective top views of connecting plates used in the assembly of the control valve system shown in FIG. 59; and

FIG. 63 is a sectional view of a control valve in accordance with the present invention which is used as a servo valve.

DESCRIPTION OF THE PREFERRED EMBODIMENTS:

First Embodiment, FIGS. 1 and 2

The first embodiment of a control valve 1 in accordance with the present invention is shown in FIG. 1 as

comprising a valve proper 2 and top and bottom covers 3 and 4 assembled into a unitary construction with the valve proper 2 by means of through bolts 5.

The valve proper 2 comprises a valve cylinder or bore 6, a passage 7 formed through the valve proper 2 in parallel with the valve bore 6, two annular grooves 8 and 9 formed around the valve bore 6, and ports 12 and 13 which hydraulically communicate with the annular grooves 8 and 9, respectively through passages 10 and 11. The ports 12 and 13 are open at the outer wall of the valve proper 2.

A spool 14 is slidably fitted into the valve bore 6 and is divided into lower and upper chambers 16 and 17 by a center partition wall 15. The spool 14 is normally located in a neutral position with respect to the bore 6. For this purpose a bush 18 is fitted into the upper end of the upper chamber 17, and a guide 19 is extended from the bush 18 into the spool 14. A centering spring 23 is loaded between a spring seat 20 fitted over the guide 19 at the base or upper end thereof, and another spring seat 22 secured in place by a flange 21 at the lower end of the guide 19. The upper spring seat 20 is pressed against a snap ring 24 fitted over the spool 14, whereas the lower spring seat 22 is pressed against the center partition wall 15. Thus the spool 14 may be normally held in a neutral position with respect to the valve bore 6 under the returning force of the centering spring 23.

30 A through bore or port 25 formed through the side wall of the spool 14 is always hydraulically communicated with the lower chamber through an interior passage 26 formed in the spool 14 below the partition wall 15 thereof, and is closed by the cylinder wall of the bore 6 between the lower and upper annular grooves 8 and 9 when the spool 14 is in a neutral position. However, as the spool 14 is moved upwardly or downwardly lengthwise in the valve bore 6 the bore or port 25 is selectively opened to the annular groove 9 or 8, so that 35 the lower chamber 16 may be hydraulically communicated with the port 13 or 12.

The top cover 3 which closes the upper opening of the valve proper 2 has a passage 29 which communicates at its one end with a pilot port 27 and which has 40 an orifice 28 disposed at its other end. The top cover 3 is further provided with the damper orifice 30 through which the passage 29 is branched to the upper chamber 17.

The bottom cover 4 which closes the bottom of the 45 valve proper 2 is provided with port 31 and a passage 32 in communication with the outlet port 31. The passages 29 and 32 are interconnected by the passage 7 in the valve proper 2, so that the pilot port 27, the passage 29, the orifice 28, the passage 7 in the valve proper 2, 50 the passage 32 and the port 31 together define a pilot flow line or passage generally indicated by 35. Seals 33 and 34 are placed at the junctures between the passage 7 and the passages 29 and 32, respectively. The pilot 55 passage 35 is communicated, through the damper orifice 30 and a through opening formed through the bush 18, with the upper chamber 17 in the valve proper 2. The port 31 in the bottom cover 4 opens not only to the undersurface of the bottom cover 4 but also into the 60 lower chamber 6 in the valve proper 2, through an orifice 37 which is secured in place at the bottom of the lower chamber 6. It should be noted that seals 38 and 65 39 are placed at the junctures between the bushing 18

and the top cover 3 and between the orifice 37 and the bottom cover 4.

Next the mode of operation will be described. When the liquid under pressure is ported through the pilot port 27 into the passage 29, it flows through the pilot passage to the port 31 at the bottom cover 4 and a pressure difference develops across the orifice 28. The pressure in the upper stream with respect to the orifice 28 is transmitted through the damper orifice into the upper chamber 17. The pressure in the lower chamber 16 is lower than the pressure in the upper chamber by a pressure difference or pressure drop across the orifice 28. Therefore the spool 14 is caused to move downwardly because of the pressure difference between the upper and lower chambers 17 and 16, and the port 25 is gradually opened to the lower annular groove 8. Therefore, when the port 12 is communicated with a hydraulic pressure source (not shown), the main flow path which is defined by the port 12, the passage 10, the annular groove 8, the port 25, the interior passage 26, the lower chamber 16, the orifice 37 and the port 31 is provided. In the port 31 the pilot and main flows are joined. The flow rate of the main flow is detected by the orifice 37 in terms of a pressure drop. The pressure in the lower chamber 16 is gradually increased so that the spool 14 is subjected to an upward thrust. Therefore the spool 14 is held stationary at a point where the upward and downward thrusts imparted to the spool 14 from the upper and lower chambers 17 and 16 are balanced.

The spool 14 is held in a balanced position when the following equation is satisfied;

$$\Delta P_2 a = kx + \Delta P_1 a$$

where

a = sectional area of spool;

kx = set or initial load applied to the centering spring; and

$\Delta P_1, \Delta P_2$ = pressure drop across orifices 37 and 28, respectively.

When the initial load of the centering spring 23 is negligible relative to the upward thrust $P_1 a$, the above equation may be rewritten in the form of

$$\Delta P_2 \sim \Delta P_2$$

Therefore the spool 14 is held in a balanced position when the pressure drops across the orifices 28 and 37 are equal, that is when the pressures in the upper and lower chambers 17 and 16 are equal.

However, if the initial load of the centering spring 23 cannot be negligible (it is assumed that the variation in load due to its spring constant be negligible), the above equation may be rewritten as follows:

$$\Delta P_2 - \frac{kx}{a} = \Delta P_1$$

Since the pressure drops across the orifices 28 and 37 are different, the spool 14 is held in a balanced position when the pressure drop across the orifice 28 is smaller than the pressure drop across the orifice 37 by the initial load of the centering spring 23, that is kx/a .

So far the pilot flow has been described as flowing from the pilot port 27 to the port 31, but even when the pilot flow is reversed the spool 14 is balanced under the conditions similar to those described above. More par-

ticularly, let it be assumed that the spool 14 is first in the neutral position shown in FIG. 1 and that the liquid under pressure is ported through the ports 31 in the bottom cover 4. Then there is a pressure drop across the orifice 28 when the pilot flow flows from the pilot passage 35 into the passage 29, so that the spool 14 is moved upwardly. Therefore, the port 25 is gradually opened to the annular groove 9. When the port 13 is communicated with a return pipe line (not shown), the main flow path which is defined by port 31, the orifice 37, the interior passage 26, the port 25, the annular groove 9, the passage 11 and the port 13 is formed. The spool 14 is subjected to a downward thrust due to the pressure drop ΔP_1 across the orifice 37. The spool 14 is held in a balanced position when the following relation is satisfied:

$$\Delta P_2 \approx \Delta P_1 \text{ or } \Delta P_2 - \frac{kx}{a} = \Delta P_1$$

Furthermore, the pressure drop ΔP_2 across the orifice 28 as well as the pressure drop ΔP_1 across the orifice 37 are in inverse proportion to the square of the cross-sectional area of the orifice, and the volumetric flow through the orifice is uniquely determined by the pressure drop across the orifice independently of the pressure of the liquid. Therefore the relation between the pilot flow Q_2 and the main flow Q_1 is given by

$$\frac{Q_1}{Q_2} = \frac{a_1}{a_2}$$

where a_1, a_2 = cross-sectional area of orifice 37, 28. It is therefore readily understood that when the ratio a_1/a_2 is suitably selected, the small pilot flow Q_2 may control the main flow Q_1 with a constant rate or amplification factor. The amplification factor a_1/a_2 may be suitably changed by various ways. For example, the orifice 28 or 37 or both may be replaced by a suitable orifice or orifices having a desired cross-sectional area, or as shown in FIG. 2 an adjusting screw 40 screwed into the passage 29 may be tightened or loosened so as to vary the cross-sectional area of the orifice 28. Alternatively, as shown in FIG. 3 a reciprocating member 41 which is reciprocated depending upon the direction of the flow may be provided for the orifice 37, so that the cross-sectional area may be automatically varied depending upon the direction of the flow. When the control valve is used as a simple module, changing the amplification factor is generally of no importance, but in case of a programmed hydraulic control system it is a very important feature that the amplification factor may be varied in a simple manner as described above. The fact that the cross-sectional area of the orifice 37 may be varied stepwise or continuously is especially advantageous in establishing the optimum band of the total flow consisting of the pilot and main flows. Since the orifice 28 detects the volumetric flow in terms of a pressure drop or difference, the pressure loss is increased as the volumetric flow is increased independently of the band used, but the suitable flow band may be provided by changing the cross-sectional area of the orifice 37.

Referring back to FIG. 1, the damper orifice 30 inter-communicating between a pilot passage 35 and the

upper chamber 17 serves to prevent a shock which is produced when the spool 14 is switched. If the upper chamber 17 and the pilot passage 35 were intercommunicated directly, the pressure difference or drop across the orifice 28 would directly act upon the spool 14 when the fluid flows from the pilot port 27. Conversely, when the fluid is introduced from the port 31 in the bottom cover 4, the pressure in the chamber 17 instantaneously drops in response to the pressure drop across the orifice 28, so that the spool 14 is subjected to this instantaneous pressure variation. Therefore, in both cases the input gain of the spool 14 becomes excessive, and the switching speed is increased considerably. As a result, a shock is produced. However, according to the present invention the damper orifice 30 is interposed between the pilot passage 35 and the upper chamber 17 whereby the liquid that flows into or out of the upper chamber may be suitably controlled, so that shock due to the switching of the spool 14 may be prevented.

Furthermore, according to the present invention the port 25 of the spool 14 is closed by the cylinder wall between the annular grooves 8 and 9 when the spool 14 is normally held in the initial neutral position under the force of the centering spring 23. When the spool 14 is moved upwardly or downwardly, the port 25 opens gradually to the annular groove 9 or 8 so that the jumping phenomenon, which tends to occur when the spool at rest is moved, may be positively prevented. Thus a smooth switching of the spool 14 may be ensured.

From the above description, the fundamental function of the control valve in accordance with the present invention will be fully understood, but it should be noted that the control valve 1 may accomplish various functions as will be described in more detail hereinafter when a suitable control valve such as a flow, pressure or directional control valve is inserted into the pilot passage. Some typical examples will be described.

1. Flow Control

1. Flow Control Valve

FIG. 4 shows a flow control system in which a flow control valve 43, provided with a non-return valve and inserted into a pilot line 42, is used as a pilot element for the control valve 1 of the present invention. The flow control valve 43 which is indicated by a symbol is a flow control and check valve of small capacity and provided with a pressure compensation system.

The main flow in a main line 44, which is switched by a direction switching or directional valve (not shown) flows into the pilot line 42 when the spool 14 is in the neutral position and then flows into the pilot port 27 after the flow rate is suitably controlled by the pilot valve 43. It flows through the pilot passage 35 toward the port 31, and the pressure drop across the orifice 28 is in proportion to the flow rate. The spool 14 starts to move downwardly so that the port 25 opens into the annular groove 8. As a result the main flow streams from the main line 44 through the ports 12 and 25 toward the port 31 and joins the pilot flow at the port 31, to flow through a load line 45 to a load 46. The flow rate of the main flow is detected by the orifice 37, and in response to the pressure drop across the orifice 37 the spool 14 is moved upward. The spool 14 is held stationary in a balanced position when the forces acting upon the top and bottom of the spool 14 equal each other. Thus the main flow is controlled at a constant ratio with respect to the pilot flow in the manner described here-

inbefore. Since the pilot flow passing through the orifice 28 is controlled at a certain flow rate by the pilot valve or control valve 43 in the pilot line 42, the total flow which consists of the main and pilot flows streaming from the port 31 to the load 46 through the line 45, is amplified by a predetermined amplification factor. That is, the total flow rate is constant. When the pressure on the side of the load 46 is increased when as the spool 14 is held in a balanced position, the pressure drop across the orifice 28 remains unchanged because the flow rate of the pilot flow is controlled by the pilot or control valve 43 in the pilot line 42. But the pressure drop across the orifice 37 is reduced due to the decrease in main flow rate caused by the pressure difference between the ports 12 and 31. As a result the spool 14 is caused to move downwardly so that the opening area of the port 25 with respect to the annular groove 8 is increased. Therefore the resistance through the passage between the port 25 and the annular groove 8 is decreased, so that the main flow rate is increased accordingly. When the pressure drop across the orifice 37 returns to the initial magnitude, that is when the flow rate of the main flow returns to its initial flow rate, the spool 14 is stopped. Since the total flow streaming from the port 31 to the load 46 consists of the pilot flow passing through the orifice 28 and the main flow passing through the orifice 37, and the main and pilot flows are so controlled that the pressure drops across them may be maintained constant, the flow rate of the total flow to the load 46 may be always maintained constant. Thus, meter-in flow control may be effected by changing the pressure drop across the orifice 37 in the main flow, which is accomplished by changing the pressure drop across the orifice 28 of the pilot flow whose flow rate in turn is controlled by the pilot flow control valve 43 in the pilot line 42.

When the direction of the main flow in the main line 44 is reversed as the spool 14 is in the neutral position, the liquid under pressure in the load 46 is returned through the pilot passage 35, the orifice 28 and the non-return valve in the pilot flow control valve 43 in the pilot line 42 to a return line. In this case the pressure drop across the orifice 28 is dependent upon the pressure in the load 46. Since the pilot line 42 is communicated with the return line, the pressure in the upper chamber 17 is decreased so that the spool 14 is moved upwardly. As a result the port 25 opens into the annular groove 9 so that the liquid under pressure in the load 46 may be returned through the port 25, the annular groove 9, the port 13, and the main line 44 to the return line.

In addition to the meter-in flow control of the type described above, a meter-out flow control may be effected as will be described with reference to FIG. 5. In this case the pilot flow control valve 43 inserted in the pilot line 42 is reversed in direction so that, when the main line 44 is connected to the pressure source, the liquid under pressure forces through the non-return valve of the pilot flow control valve 43 into the port 27 and flows through the orifice 28 and the pilot passage 35 into the load 46. Then the spool 14 is caused to move downwardly so that the port 25 is opened into the annular groove 8. As a result the main flow flows into the load 46. Conversely, when the main line 44 is connected to the return line, the liquid under pressure in the load 46 returns to the return line through the orifice 28 and the pilot flow control valve 43. Since the pilot

flow rate is controlled at a constant magnitude by the flow control valve 43, the pressure drop across the orifice 28 may be maintained at a constant magnitude. Therefore the spool 14 is moved upwardly so that the port 25 is opened into the annular groove 9. Consequently the main flow, whose flow rate with respect to that of the pilot flow rate is constant, is provided. Thus the meter-out flow control may be effected.

II. Throttle Valve

When a throttle valve is inserted instead of the pilot control valve 43 in FIGS. 4 and 5, a throttle valve assembly taking full advantage of the control valve 1 of the present invention may be provided. The mode of operation of this throttle valve assembly will not be described in this specification since it is apparent to those skilled in the art from the description of the flow control valve provided above. In the throttle valve there should be disposed a nonreturn valve in a desired direction, as is the case of the pilot flow control valve.

III. Distribution and Collection Valves

Referring to FIG. 6 a control valve generally designated by 1a is a combination of two control valves 1 described hereinbefore with reference to FIG. 1, except that the ports 12 and 13 are intercommunicated respectively. The pilot lines 42 are selectively communicated with a hydraulic pressure source 49 or a reservoir 50 through a conventional small-capacity distribution-collection valve 47 and a switching valve 48. When the switching valve 48 is switched to the right position so as to communicate the pilot lines 42 with the hydraulic pressure source 49, liquid under high pressure from the pressure source 49 is divided into two pilot flows at a predetermined ratio by the distribution valve 47, and the two pilot flows stream through the orifices 28 and the pilot passages 35 to two loads 46, respectively. Therefore the spool 14 in each control valve unit is moved downwardly and held at a balanced position in a manner substantially similar to that described hereinbefore. Then two main flows, whose stream rate ratio is dependent upon the distribution ratio at which the liquid under pressure is divided into the two pilot flows flow from the pressure source 49 through the common port 12 to the two loads 46, respectively, because the degrees of opening of the ports 25 to the annular grooves 8 are in proportion to the flow rate ratio between the two pilot flows. Thus the control valve 1a of the present invention functions as a distribution valve.

Conversely, when the switching valve 48 is switched to the left position the return flows from the loads 46 flow into the reservoir through the pilot passages 35, the orifices 28 and the collection valve 47 in which the two return flows are joined or collected at a predetermined ratio. Therefore the spools 14 are moved upwardly, depending upon the return-flow-collection ratio explained above, so that the main return flows stream from the loads 46 through the ports 25, the annular passages 9 and the common port 13 at such a flow-rate-ratio in proportion to the pilot-flow-collection ratio. Thus the control valve 1a of the present invention functions as a collection valve. It will be apparent that the flow rates in the two control valve units may be readily varied by changing the cross sectional areas of the orifices 28 in the manner described hereinbefore.

So far the control valve 1a has been described as functioning as a distribution-collection valve, but it will be understood that the control valve 1a may be used as

a distribution or collection valve only, by replacing the pilot distribution-collection valve 47 with a pilot valve of the type shown in FIG. 6A or 6B. In the instant embodiment, the control valve 1a comprising two control valve units is used, but it will be understood that two control valves 1 of the type described with reference to FIG. 1 may be used, particularly when they are desired to be assembled with the loads 46.

2. Pressure Control

IV. Relief Valve

FIG. 7 shows an arrangement of hydraulic circuit in which the control valve 1 in accordance with the present invention is used as a relief valve. The pressure in the main line 44 is increased in response to the overload of the load 46, so that a pilot relief valve 51 inserted in the pilot line 42 is opened. As a result, a pilot flow from the load 46 passes the orifice 28 and the pilot relief valve 51 and flows into the reservoir 50. The spool 14 is moved upwardly so that the port 25 opens into the upper annular passage 9. Therefore the liquid under high pressure in the load 46 is relieved into the reservoir 50 through the port 13. Thus the control valve 1 functions as a relief valve.

As a variation of the control valve shown in FIG. 7, the lower end of the spool 14 is extended so as to make contact with the orifice 37 and a spring is interposed between the spool 14 and the bush 18 instead of the centering spring 23. In the variation of the type described, it is not required to control the flow rate so that the cross-sectional area of the orifice 37 may be increased, or the orifice 37 itself may be eliminated. However, when the control valve 1 is used as an overload relief valve for use as a counter weight, the orifice 37 is disposed so as to control the flow to be relieved. The control valve 1 may accomplish every function of the conventional overload relief valves. Furthermore, when the pilot line 42 is directly connected to the reservoir 50, the control valve may function in a very reliable manner even when the pressure of the main relief flow is considerably high. Moreover, erratic operation may be prevented even when the pressure of the relief flow becomes high, by contrast to the conventional balance-piston type relief valves. Even when the pressure of the relief flow becomes higher than the load pressure in operation, the spool 14 may be instantaneously returned so that the counter flow may be prevented, thereby preventing the abnormal pressure rise in the load. The control valve 1 is particularly advantageous when it is used as an overload relief valve in a hydraulic cylinder or motor circuit.

V. Reducing Valve

Referring to FIGS. 8 and 9, a small-capacity reducing valve 52 is inserted into the pilot line 42. When the secondary pressure at the port 31 (see FIG. 8) or the secondary pressure at the port 13 (see FIG. 9) is less than a predetermined pressure level, the pilot reducing valve 52 is opened wide so that the liquid under high pressure flows through the pilot passage 35 from the hydraulic pressure source 49 into the secondary. Therefore the spool 14 moves downwardly (see FIG. 8) or upwardly (see FIG. 9) in response to the pressure drop across the orifice 28, so that the port 25 opens to the annular groove 8 or 9. Consequently the liquid under pressure may be directly forced into the secondary line. When the pressure on the secondary side is in excess of a predetermined pressure, which is dependent upon the degree of pressure reduction made by the reducing valve

52, the pilot reducing valve 52 is closed so that no pilot flow flows into the pilot passage 35. As a result there is no pressure drop across the orifice 28, so that the spool 14 is immediately returned to its initial position, whereby the flow of liquid under pressure to the secondary line is interrupted. Thus the control valve 1 may function as a reducing valve while controlling the secondary pressure at the port 31 or 13, depending upon the pressure reduction made by the pilot reducing valve 52. The variation of the control valve described with reference to the relief valve may be used, and the orifice 37 may be eliminated. However, when an accumulator is attached to the primary line the orifice 37 is used in order to prevent the excess and rapid flow of liquid under pressure when the secondary pressure is varied.

VI. Overload Mechanism

The use of the control valve as a relief valve has already been described. FIG. 10 shows a hydraulic circuit of an overload mechanism which is used for supplying the liquid under pressure without fail to the opposite direction when a directional control valve 53 is in a blocking position. Such a hydraulic circuit as described above is used in a hydraulic motor circuit. In FIG. 10 it is assumed that the pressure in the left circuit of the hydraulic motor 54 be increased so that a pilot overload relief valve 51 in the left pilot line 42 is opened. Then the pilot flow flows through the left pilot passage 35, and the left spool 14 moves upwardly in response to the pressure drop across the left orifice 28 so that the port 25 opens to the annular groove 9. Therefore the liquid under pressure is returned to the reservoir 50 through the common port 13. The flow discharged from the left pilot relief valve 51 forces through a left non-return valve 55 into the right pilot line 42, the right pilot passage 35 and the right circuit of the hydraulic motor 54. Therefore the spool 14 moves downwardly in response to the pressure drop across the right orifice 28, so that the port 25 opens to the annular groove 8. As a result the liquid under pressure is supplied from the pressure source 49 into the right circuit of the hydraulic motor 54 through the common port 12. The discharge side of the overload relief valve 51 is connected via a check valve 56 set to a low pressure to a reservoir, so that when the pressure in the right circuit of the hydraulic motor 54 is increased as the fluid under pressure is supplied thereto from the pressure source 49, the pilot flow forces through the non-return valve 56 into the reservoir and the pressure drop across the right orifice 28 disappears. As a result the spool 14 returns to its initial position so that the pressure increase in the right circuit may be prevented. So far the mode of operation has been described only when the pressure is increased in the left circuit of the hydraulic motor 54, but the mode of operation when the pressure in the right circuit is increased will be readily understood by those skilled in the art because the hydraulic circuit shown in FIG. 10 is symmetrical.

VII Floating Mechanism:

FIG. 11 is a diagram of a hydraulic circuit for floating or releasing a load from the circuit. When a directional control circuit 57 is switched to the extreme right float position, the right and left pilot lines are short-circuited and communicated only to the reservoir 50 so that both of the right and left spools 14 are not actuated. However, if external force is exerted upon the load 46, the pilot flow flows from the left circuit of the load 46

through the left pilot flow passage 35 so that a pressure drop across the left orifice 28 is produced. Therefore the left spool 14 is moved upwardly so that the port 25 opens to the annular groove 9. Therefore the liquid 5 under pressure in the left circuit of the load 46 may be directly discharged or returned to the reservoir 50 from the common port 13. The liquid under pressure passing through the left pilot flow passage 35 flows into the right pilot passage 35 and into the right circuit of the load 10 circuit 46. In response to the pressure drop across the right orifice 28, the spool 14 is caused to move downwardly so that the right port 25 opens to the right annular groove 8. Therefore the liquid under pressure 15 is directly supplied to the right circuit of the load 46 from the hydraulic pressure source 49. When the excess hydraulic pressure is applied to the right circuit of the load 46, the pressure in the latter is increased so that the pilot flow passing through the left pilot passage 28 forces through a low-pressure non-return valve 56 20 into the reservoir 50. Therefore the pressure drop across the right orifice 28 disappears, so that the spool 14 may be immediately returned to its initial position. Thus the excess pressure rise in the right circuit of the load 46 may be positively prevented. The mode of operation 25 when external force is applied to the load 46 so as to increase the pressure in the left circuit thereof, will be apparent from the above explanation so that no description will be made in this specification. Thus the load 46 may be floated by connecting either the right 30 or the left circuit of the load 46 to the reservoir 50 and connecting the other circuit to the hydraulic pressure source 49.

3. Flow Direction Control

VIII. Directional Control Valve

35 FIGS. 12 and 13 are the diagrams of a three-port three-position directional control valve and four-port three-position directional control valve hydraulic circuits. Referring to FIG. 12, a three-port three-position pilot directional control valve 58 of a small capacity is 40 inserted in the pilot line 42. When the high-pressure fluid flows from the hydraulic pressure source 49 through the pilot line 42 and the pilot passage 35 to the load 46, the spool 14 moves downwardly in response to the pressure drop across the orifice 28 so that the port 45 25 opens to the annular groove 8. Therefore the high-pressure fluid may be directly supplied to the load 46 through the port 12. Conversely, when the pilot valve 58 is switched to the left position, the liquid under pressure flows from the load 46 to the reservoir 50 through 50 the pilot passage 35 and the pilot line 42. In response to the pressure drop across the orifice 28, the spool 14 is moved upwardly so that the port 25 opens to the upper annular groove 9. Therefore the high-pressure liquid is returned directly from the load 46 to the reservoir 55 through the port 13.

55 Referring to FIG. 13, a four-port three-position pilot valve 59 of a small capacity is inserted into the pilot lines 42 of the control valve 1a of the type described hereinbefore with reference to FIG. 6. When the pilot valve 59 is switched to the right position, the fluid under pressure flows from the pressure source 49 to the left of the load 46 through the left pilot line 42 and the left pilot passage 35. In response to the pressure drop across the left orifice 28 in the left pilot passage 35, the spool 14 is caused to move downwardly so that the high-pressure liquid from the hydraulic pressure source 49 may be directly supplied to the left side of the load 60 65

46 in the manner described hereinbefore. Conversely, the high-pressure liquid in the right side of the load 46 flows into the reservoir through the right pilot passage 35 and line 42. In response to the pressure drop across the right orifice 28 in the right pilot passage 35, the right spool 14 moves upwardly so that the right port 25 opens to the upper annular groove 9. Therefore the liquid under pressure in the left chamber of the load 46 may be directly returned to the reservoir 50 through the port 13. The mode of operation when the pilot valve 59 is switched to the left position will be apparent, to those skilled in the art, from the above explanation.

When the control valve 1a of the present invention is used only for the on-off operation as described above, the orifice 37 may be eliminated, but the orifice 37 must be used in order to improve the response by adjusting the cross sectional area thereof when the pilot valve is closed. It must also be used when a flow-rate-ratio control type servo valve is used as a pilot directional control valve 59.

4. Composite Control

X. Composite Four-Port-Three Position Control Valve:

So far only one pilot valve has been used with the control valve 1 or 1a of the present invention, but as shown in FIG. 14 various hydraulic valves such as a flow control valve 43, a directional control circuit 59, an overload relief valve 51 and a reducing valve 52 may be inserted into the pilot lines 42 so that their functions may be accomplished by the control valve 1a. However the mode of operation of the hydraulic circuit shown in FIG. 14 will not be described in this specification because it is apparent to those skilled in the art from the explanation of the various modes of operation described hereinbefore.

From the above explanation, it is seen that when a small-capacity pilot valve or valves are inserted into a pilot line or lines, the control valve in accordance with the present invention may be used as a large-capacity control valve accomplishing the same function as that of the pilot valve. Furthermore, when various hydraulic valves are inserted, the control valve in accordance with the present invention may be used as a composite hydraulic control valve capable of accomplishing the various functions of the pilot valves. The universal type control valves capable of versatile function in accordance with the present invention may be standardized. The pilot valves may be assembled with the control valves or may be disposed separately for a hydraulic remote control system, without adversely affecting the overall function. The pilot valves may be intercommunicated with the control valves by pilot lines of a small diameter. Furthermore the problems of shock, surge and the like which are often encountered in the large-capacity control valves may be positively overcome. The flow-rate-amplification band may be readily varied by changing the cross-sectional area of an orifice in the pilot passage, in the main passage, or in both passages. The small-capacity pilot valves can control in a reliable manner all of the versatile functions of a hydraulic system in which a plurality of control valves in accordance with the present invention are combined for the specific purposes. Thus the hydraulic control circuit may be designed so as to be compact in size and light in weight.

The use of the control valve in accordance with the present invention as a relief valve has been described,

and the control valve of the present invention is also used as a main relief valve. It is often desired that the main relief valve is provided with an unloading or carry-over function. Therefore the present invention also provides a control valve capable of accomplishing such functions, as will be described in more detail hereinafter with reference to FIGS. 15-20.

First referring to FIG. 15, a control valve generally designated by 101 is shown as comprising a valve proper 102, and top and bottom covers 103 and 104 assembled into a unitary construction by means of bolts 105.

The valve proper 102 comprises a valve cylinder or bore 106, a passage 107 vertically bored through the valve proper 102, an annular groove 108 formed around the valve bore 106, a discharge port 112 communicated through a passage 110 with the annular groove 108, and an actuating port 161 communicated with an inlet port 131 through a passage 160, a seal 163 being secured in place in the joint between the passage 160 and the inlet port 131. The ports 112 and 161 are opened at the side wall of the valve proper 102. A spool 114 which is slidably fitted into the valve bore 106 is divided into lower and upper chambers 116 and 117 by a center partition wall 115, and a spring 123 is loaded between the undersurface of the top cover 103 and the upper surface of the partition wall 115 so that the lower end of the spool 114 is normally pressed against a seal holder 137 secured in place at the bottom of the valve bore 106. That is, the spool 114 is normally held in the lowermost position. A port 125 bored through the side wall of the spool 114 is always communicated with the lower chamber 116 and opens to the annular groove 108 only when the spool 114 is moved upwardly against the spring 123, so as to communicate the lower chamber 116 with the discharge port 112.

The top cover 103 has a passage 129 one end of which is communicated with a pilot port 127 and the other end of which is communicated with the vertical passage 107 through an orifice 128. The passage 129 is also communicated with the upper chamber 117 through a damper orifice 130.

The bottom cover 104 has a passage 162 intercommunicating between the port 131 and the lower chamber 116, and a passage 131 branched from the passage 162 and communicated with the passage 107 at the lower end thereof. When the covers 103 and 104 are joined to the valve proper 102, seals 133, 134, 138 and 139 are placed at the upper and lower ends of the passage 107 and cylinder bore 106, respectively. A pilot passage generally designated at 135 is defined by the inlet port 131, the passages 162 and 132 in the bottom cover 104, the vertical passage 107, the orifice 128, the passage 129 and the pilot port 127. The pilot passage 135 is intercommunicated with the upper chamber 117 through the damper orifice 130.

The inlet port 131 is connected to a hydraulic pressure source 149; the discharge port 112 to a reservoir 150; and the actuating port 161 to an actuating circuit 164. The pilot port 127 is communicated with the reservoir 150 through a pilot line 142 having a pilot switching valve 165 inserted therein. Therefore, as long as the intercommunication between the pilot port 127 and the reservoir 150 is interrupted by the pilot valve 165, the pressures in the lower and upper chambers 116 and 117 are equal because they are intercommunicated with each other through the bypass passage

162, the passage 132, the vertical passage 107, the passage 129 in the top cover 103 and the damper orifice 130. Thus the spool 114 is held in the lowermost position as shown in FIG. 15 under the force of the spring 123. A high-pressure stream of liquid flows from the hydraulic pressure source 149 to the actuating circuit 164 through the inlet port 131, the passage 160 and the actuating port 161. Thus the control valve 101 is maintained in the "on-load" state.

When the pilot valve 165 is switched so as to communicate the pilot port 127 to the reservoir 150, the pilot flow passes the pilot passage 135 and the pilot line 142 to the reservoir 150 from the hydraulic pressure source 149, and a pressure drop or difference is produced across the orifice 128. Therefore, there arises a pressure difference between the lower and upper chambers 116 and 117 so that the spool 114 is moved upwardly, compressing the spring 123. The port 125 opens to the annular groove 108 so that the liquid under pressure may now flow from the pressure source 149 directly to the reservoir 150 through the intake port 131, the passage 162, the lower chamber 116, the port 125, the passage 110 and the discharge port 112. Therefore the control valve 101 is maintained in the "unloaded" state by this main flow.

A pilot main relief valve 166 is inserted into the pilot line 142 between the pilot port 127 and the pilot valve 165. Therefore, when the main relief valve 166 is opened due to the abnormal pressure in the actuating circuit 164 in the unloaded state, the pilot flow passes from the pressure source 149 through the pilot passage 135, the pilot line 152 and the main relief valve 166 into the reservoir 150. Therefore, in response to the pressure drop across the orifice 128 in the pilot passage 135 the spool 114 is caused to move upwardly in the manner described above, so that the port 125 opens to the annular groove 108. The abnormal pressure in the actuating circuit 164 is now released through the actuating port 161, the passages 160 and 162, the lower chamber 116, the passages 160 and 162, the lower chamber 116, the port 125, the passage 110 and the discharge port 112 into the reservoir 150. Thus the control valve 101 in accordance with the present invention functions as an unloading valve and a main relief valve.

Carry-Over Control Valve

So far the mode of operation of the control valve 101 as an unloading valve has been described and an unloading-main-relief valve, but the control valve 101 may be also used as a carry-over valve, as will be described in more detail hereinafter. For example, in a hydraulically driven vehicle it is highly desired to minimize the power loss because there has not been available a satisfactory device for effectively cooling the high-pressure liquid used, even though the space of a reservoir cannot be increased beyond a certain limit and because it is required to prevent as much as possible the increase of pressure of the hydraulic pressure source. Furthermore, in the case of construction equipment which has recently been developed to accomplish various functions, this requires the maximum power with full capacity to accomplish some functions but at some times it requires only a small power with a fraction of its capacity. Therefore, in hydraulically driven vehicles including such construction equipment, the so-called "carry-over" valve mechanism is employed in

order to collect the high-pressure liquids from a plurality of hydraulic power sources so as to provide a greater horse power utilizing the full capacity of all available high-pressure liquids. However, the conventional carry-over system has a defect in that, when the actuators in the actuating circuits in the front stage group which is selected and energized reach the stroke end or the main relief valve is opened, the carry-over to the rear stage group cannot be effected unless the directional control valve is once returned to its neutral position. Therefore, all of the high-pressure liquid is returned to the reservoir during the carry-over operation so that an overheating problem arises. The above and other problems encountered in the conventional carry-over valves 15 may be overcome by the control valve in accordance with the present invention.

Referring to FIG. 16, both the pilot and main flows are carried over to the rear stage group from the pilot and discharge ports 127 and 112, so that in the unloaded state the high-pressure liquid in the first group 20 may be all carried over to the second group. Furthermore, in the unloaded state a substantial part of the high-pressure fluids is carried over to the second group as a main flow, even when the pilot main relief valve 166 is opened, so that a very small quantity of pilot flow 25 is returned to the reservoir 150. Thus the control valve 101 of the present invention may be used as a main-relief-carry-over valve.

Furthermore, the control valve 101 may be modified 30 so as to be used as a valve which may accomplish the functions of a main relief valve, an unloading valve and a carry-over valve. This will be described with reference to FIG. 17. The control valve 101a is substantially similar in construction to the control valve 101 shown 35 in FIG. 15, except that an additional annular groove 109 is formed around the valve bore 106 in communication therewith and also in communication through a passage 111 with a port 113 which is now used as a discharge port connected to the reservoir 150 and a port 167 formed through the wall of the spool 114. The port 112 is used as a carry-over port and connected through 40 a check valve 169 to the second group. When the spool 114 is moved upwardly over a distance slightly longer than the stroke of the spool of the control valves 45 described hereinbefore of the type having only one port in the spool, the port 167 opens to the annular groove 109 so that the lower chamber 116 is communicated with the discharge port 113 through the port 167, and the passage 111.

When the switching valve 165 is opened so that the first group is deactivated, the spool 114 is moved upwardly in response to the pressure difference across the orifice 128 in the pilot passage 135 through which the flows the pilot flow, so that the port 125 opens to the annular groove 108. Therefore, the liquid under pressure in the first group may be carried over to the second group. Furthermore, when the second group, or groups succeeding to the second group, are in the unloaded stage, the pilot flow is returned to the reservoir 55 150 through the unloaded group or groups so that the pilot flow is increased in volume. As a result the pressure drop across the orifice 128 is increased so that the spool 114 is further moved upwardly. The upper port 60 167 is opened to the upper annular groove 109, so that the high-pressure liquid in the first group may be directly returned to the reservoir 150. Thus the control valve 101a functions as an unloading valve.

When the pressure in the first group is increased so that the pilot main relief valve 166 is opened when the first group is actuated with the switching valve 165 closed, the pilot flow passes through the pilot passage 135 so that the port 125 of the spool 114 opens to the annular groove 108. Then the liquid under pressure in the first group is carried over to the second group. Furthermore, when the second group and the groups succeeding to the second group is or are actuated and the actuating pressure is lower than the relief-set pressure of the first group, the spool 114 functions like a sequence valve so as to maintain the pressure in the first group while the port 125 slightly opens to the annular groove 108 when the pressure difference between the first and second groups is great, or the port 125 opens wide to the annular groove 108 when the pressure difference is small. Thus an automatic adjustment may be accomplished.

When under the above conditions the actuating pressure in the second group and the groups succeeding to the second group becomes in excess of the relief set pressure for the first group, the flow of the high-pressure liquid to the second group and to groups succeeding to the second group is interrupted, so that the pilot flow returning through the pilot passage 135 and the main relief 166 is increased in volume. As a result the pressure drop across the orifice 128 is increased so that the spool 114 is moved further upwardly so as to open the port 167 to the annular groove 109. Therefore, the liquid under pressure in the first group is returned through the discharge port 113 to the reservoir 150. Thus the control valve 101a now functions as the main relief valve for the first group, independently of the second group. Since a check valve 169 is inserted into the line connecting the carry-over port 112 to the second group, the high-pressure liquid in the second group is not permitted to flow into the first group. Thus it will be understood that the control valve 101a functions as a main relief valve, an unloading valve and a carry-over valve.

However in the hydraulic circuit described hereinabove with reference to FIG. 17, when the actuating pressure in the second group becomes in excess of the relief pressure set for the first group is deactivated while the high-pressure liquid in the first group is carried over the second group, the pilot relief valve 166 is opened so that the control valve 101a functions as a main relief valve. Therefore, the power loss in the first group is increased. This defect may be overcome by a hydraulic circuit shown in FIG. 18.

Referring to FIG. 18, a pressure switching valve 170 is inserted into the pilot line 142 so that when the actuating pressure in the second group becomes in excess of a predetermined level, the pressure switch valve 170 is switched so as to return the pilot flow into the reservoir 150. Therefore, when the actuating pressure in the second group becomes in excess of a predetermined level, the pilot port 127 is communicated with the reservoir 150 so that the spool 114 is moved upwardly to open the port 167 to the annular groove 109. Therefore, the liquid under pressure in the first group may be directly returned through the discharge port 113 to the reservoir 150. Thus the control valve 101a functions as an unloading valve so that the power loss may be minimized.

In the hydraulic circuits shown in FIGS. 17 and 18, when the carry-over from the first to the second group

is not required, that is, when the high-pressure liquid required for actuating the second group is sufficiently supplied from its own hydraulic pressure source with the main switching valve in the second group not being fully opened, it is meaningless and not preferable to carry over the high-pressure liquid from the first to the second group because the temperature of the high-pressure liquid rises. This problem may be overcome by hydraulic circuits shown in FIGS. 19 and 20.

Referring to FIGS. 19 and 20 a pilot valve 171 is inserted into the pilot line 142 so that the pilot flow may be normally returned to the reservoir 150, thereby maintaining the control valve 101a in the unloaded state. Furthermore, when the main switching valve in the first group is so actuated that the high-pressure liquid required in the second group is in excess of the high-pressure liquid supplied from the hydraulic pressure source for the second group, the pilot valve 171 is switched mechanically (see FIG. 19) or electrically (See FIG. 20) in response to the signal from the main switching valve so that the pilot flow from the first group is introduced into the second group to carry over the main flow. Therefore, when the high-pressure liquid required in the second group is sufficiently supplied from its own hydraulic pressure source, a quantity of high-pressure liquid equal to the sum of the quantities of the hydraulic pressure sources for the first and second groups minus the high-pressure liquid required is relieved without causing temperature rise. Therefore the loss is limited only in the second group.

In the hydraulic circuits described hereinbefore the pilot and main flows forming the first group are introduced into the second group through separate lines, but when the first and second groups are spaced apart from each other, it is not preferable to interconnect between the first and second groups through the two separate lines. Therefore it is preferable to join the pilot and main flows from the first group and pass them through a single line to the second group. Therefore, the hydraulic circuits incorporating the control valves 101 or 101a in accordance with the present invention, for permitting the control valves to operate as a main relief valve as well as an unloading valve, may be designed extremely compact in size. Furthermore, the control valve in accordance with the present invention may function as a carry-over valve and the hydraulic carry-over circuits may be designed so as to attain maximum efficiency depending upon the purposes of use.

In the above embodiments the various pilot control valves are inserted into the pilot line connected to the pilot port of the control valve, so that the latter may amplify the functions of the pilot valves. However, the standardization of the hydraulic control valves will be much facilitated if the various standardized pilot control valves are unitized with the control valves of the present invention. Therefore the present invention also provides a control valve of the type described above.

Referring to FIGS. 21, 22, and 23, a control valve is shown as comprising a valve proper 202, and top and bottom covers 203 and 204 assembled into a unitary construction with bolts 205.

Next referring to FIGS. 24-29, the valve proper 202 comprises a pair of vertical valve cylinders or bores, a pair of vertical passages 207 bored through the valve proper 202, a pair of annular grooves 208 and 209 formed around the pair of valve bores 206, two passages 244 and 245 in communication with the lower an-

nular groove 208, and two passages 246 and 247 in communication with the upper annular groove 209. The passages 244 and 246 open at the bottom of the valve proper 202, whereas the passages 245 and 247 open at the top of the valve proper 202. In order to avoid interference of these passages 244-247 with the pairs of valve bores 206 and annular grooves 208 and 209, as best shown in FIGS. 27-29, the annular groove 208 is extended arcuately outwardly and reduced arcuately inwardly between the pair of valve bores 206, so as to provide an extended portion 208a and a reduced portion 208b (see FIG. 28) in opposed relation. The passages 245 and 246 which open at the bottom of the valve proper 202 are bored in the extended and reduced areas 208a and 208b, respectively. Similarly the upper annular groove 209 is extended partly outwardly arcuately so as to provide an extended area 209a on the same side with the reduced area 208b of the lower annular groove 208 (see FIG. 29). The passage 245 which opens at the bottom of the valve proper 202 is bored to open in this extended area 209a. The passage 245 is bored so as to open at the extended area 208a (see FIG. 28). The passage 247 is bored from a suitable position on the top of the valve proper 2 to the upper annular groove 209.

Furthermore, the valve proper 202 is provided with through boxes 250 for passing the bolts 205, and with tapped holes 248 and 249 at the top and bottom for securely holding in place the top and bottom covers 203 and 204, respectively.

Referring back to FIG. 21 a spool 214 having a port 225 formed through the side wall thereof is slidably fitted in each valve bore 206, the latter being divided into lower and upper chambers 216 and 217 by a center partition wall 215. A bush 218 is fitted into the valve bore 206 at the upper end thereof and a guide 219 is extended from the bush into the upper chamber 217 of the spool 214. A centering spring 223 is loaded between an upper spring seat 220 fitted over the guide 219 at the base thereof, and a lower spring seat 222 fitted over the guide 219 at a flange 221 formed at the lower end thereof. The spring seat 220 is pressed against a snap ring 224 fitted over the spool 214 whereas the spring seat 222 is pressed against the center partition wall 215 of the spool 214. Thus the spool 214 may be held in a neutral position under the force of the centering spring 223. The bore 225 formed through the side wall of the spool 214 is always communicated with the lower chamber 216 through an interior passage 226 within the spool 214. Furthermore the bore 225 is normally closed with the side wall of the cylinder 206 between the lower and upper annular grooves 208 and 209 when the spool 214 is in the neutral position. However, as the spool 214 is moved downwardly or upwardly the bore 225 opens to the lower or upper annular groove 208 or 209.

Next referring to FIGS. 30-33, the top cover 203 which closes the top of the valve proper 202 will be described. The top cover 203 is provided with a valve mounting seat 251, at which open a pilot inlet and discharge ports 252 and 253 and a pair of pilot ports 254. These ports 252-254 must be bores so that they are in alignment with the ports or the like of a standardized solenoid valve or the like which is attached to the control valve 202. The top cover 203 is further provided with holes 255 and 256 in alignment with the corresponding tapped holes 248 and through bores 250 of

the valve proper 202. The pilot inlet and discharge ports 252 and 253 and the pair of pilot ports 227 are communicated with the passages 245, 247 and 207 of the valve proper 202, respectively. More particularly, 5 the inlet port is bored vertically through the top cover 203 whereas the pilot discharge port 253 and the pair of pilot ports 227 are communicated with lateral passages 258 and 229, respectively. The passage 229 in communication with the pilot port 227 is opened 10 through an orifice 228 at the bottom of the top cover 203. The passage 229 is further provided with a damper orifice 230 opening at the bottom of the top cover 203.

As best shown in FIG. 22, the top cover 202 is firmly secured on the top of the valve proper 202 with bolts 15 242 screwed into the tapped holes 248 in the valve proper 202 through the holes 255. Thus the passage 257 in communication with the inlet port 252 of the top cover 203 is communicated with the passage 245 in the valve proper 202; the discharge port is communicated 20 through the passage 258 with the passage 247; and the pilot ports 227 are communicated through the passages 229 and orifices 228 with the passage 207. Furthermore, the pasages 229 are communicated with the upper chambers 217 in the valve bores 206 through the 25 damper orifices 230.

Next referring to FIGS. 34-37, the bottom cover or sub-plate 204 which closes the bottom of the valve proper 202 will be described. The bottom cover 204 generally comprises a cover proper 259 and a flange 30 260. The cover proper 259 is provided with two output ports 231 and inlet and discharge ports 212 and 213, all disposed symmetrically as best shown in FIG. 35, passages 232 which are bored at a slant through the cover proper 259 from the upper surface thereof to the 35 output ports 231, and through bores 261 and tapped holes 262 which are in alignment with the tapped holes 249 and the through bores in the valve proper 202. The bottom cover 204 is attached to the valve proper 202 with bolts 243 screwed into the holes 261 after an orifice 237 has been screwed into the valve bore 206 at 40 the lower end thereof in the valve proper 202. The output ports 231 are communicated with the lower chambers 216 defined in the valve bores 206; the slanted passages 232 are communicated with the vertical 45 through holes 207 in the valve proper 202; and the inlet port 212 is communicated with the passage 244 in communication with the lower annular groove 208, whereas the discharge port 213 with the passage 246 is in communication with the upper annular groove 209 50 in the valve proper 202.

The control valve 202 may be attached to a suitable member with bolts or screws inserted through holes 263 bored through the flange 260 at four corners (see FIG. 35).

The assembly of the top cover 203, the valve proper 202 and the bottom cover 204 may be summarized as follows: The top and bottom covers 203 and 204 are attached to the top and bottom of the valve proper 202 with the bolts 242 and 243, and the through bolts 205 60 which are passed through the through holes 256 and 250 in the top cover 203 and valve proper 202 and screwed into the tapped holes 262 in the bottom cover 204. (see FIGS. 22 and 23).

The intercommunications between the ports in the top and bottom covers 203 and 204 may be summarized as follows: The inlet port 212 of the bottom cover 204 is communicated through the passages 244, the an-

nular groove 208 and the passage 245 in the valve proper 202, and further through the passage 257 in the top cover 203 with the pilot inlet port 252 of the top cover 203. The discharge port 213 of the bottom cover 204 is communicated with the pilot discharge port 253 of the top cover 202 through the passage 246, the annular groove 209, the passage 247 in the valve proper 202 and the passage 258 in the top cover 203. The output port 231 of the bottom cover 204 is communicated with the lower or upper annular groove 208 or 209, depending upon whether the spool 214 moves downwardly or upwardly through the lower chamber, the interior passage 226 and the port 225, and then is communicated with the pilot inlet or discharge port 252 or 253 of the top cover 202. The pilot port 227 of the top cover 203 is communicated through the passage 229 and the orifice 228 in the top cover 203, the vertical passage 207 in the valve proper 207, and the slanting passage 232 in the bottom cover 204 with the outlet port 231 in the bottom cover 204.

Next referring to FIGS. 38, and 40, some of the valve assemblies generally designated by 470 and adapted to be used together with the control valve 201 will be described hereinafter. The valve assemblies 470 are of a buildup type, stacked or integrated valve unit provided with a specially designed subplate.

First referring to FIG. 38 illustrating a relief valve assembly comprising two relief valve units 476, a valve body 471 is provided with an inlet port 472, discharge ports 473, outlet ports 474 and through bores 475 for passing therethrough bolts or screws for assembly or installation. These ports and thorough holes are all bored in alignment with the corresponding ports and holes of a solenoid valve to be attached to the valve assembly 470. The relief valve units 476 are interposed between the outlet and discharge ports 474 and 473.

FIGS. 39 and 40 illustrate a flow control valve assembly 470. A valve body 471' is provided with an inlet port 472', discharge ports 473', the outlet ports 474' and through bolt or screw holes 475', all of which are bored in alignment with the corresponding ports and holes of a solenoid valve to be attached to valve assembly 470. Flow control valve units 476' are interposed between the inlet port and the outlet ports 474'.

Referring to FIG. 41, the valve assembly 470 is stacked upon the control valve 201, and a solenoid valve 500 is stacked upon the valve assembly 470. They are securely joined together with bolts (not shown) fitted into the tapped holes 254 and the bolt holes 475 or 475'.

The inlet port of the subplate or bottom cover 204 of the control valve 201 is communicated with a hydraulic power source, such as a hydraulic pump; the discharge port 213, with a reservoir such as a tank; and the outlet ports 231, with an actuator such as a hydraulic motor or cylinder. While the solenoid valve 500 is in the neutral position, there is no flow in the control valve 201 so that the latter is not actuated, because the flow path leading from the input port 212 is closed as the annular groove 208 is closed by the spool 214 and because the flow path consisting of the annular groove 208, the passage 245, the pilot input port 252 of the top cover 203 and the input port 472 or 472' of the valve assembly 470 is interrupted at the solenoid valve 500.

However, when the solenoid valve 500 is energized so that the inlet port 472 or 472' of the valve assembly 470 is communicated with one of the two output ports

474 or 474', the high-pressure liquid from the hydraulic pressure source flows as a pilot flow into the actuator through the flow path consisting of the input port 212, passage 244, annular groove 208, passage 245 and pilot input port 252 of the control valve 201, the input port 472 or 472' of the valve assemblies 470, the solenoid valve 500, the output ports 474 and 474', the pilot port 227, orifice 228, passage 207, passage 232 and output port 231 in the control valve 201. The volumetric flow of the above pilot flow is detected in terms of the pressure drop across the orifice 228.

The high-pressure liquid from the actuator is returned to the reservoir through the flow path consisting of the other output port 231, passages 232 and 207, orifice 228, and pilot port 227 of the control valve 201, the other output ports 474 and 474' of the valve assemblies 470, the solenoid valve 500, the discharge ports 473 and 473' of the valve assemblies 470, the discharge port 253, the passage 247, the annular groove 209, the passage 246, and the discharge port 213 in the control valve 201. This return flow serves as a pilot flow whose flow rate is detected by the other orifice 228 in terms of a pressure drop.

Depending upon the pressure drop across one orifice 228 the spool 214 on the input or supply side is moved downwardly, so that the port 225 opens to the annular groove 208. Similarly, in response to the pressure drop across the other orifice 228 in the return pilot flow path, the spool 214 on the side of discharge flow is moved upwardly, so that the port 225 opens to the upper annular groove 209. Therefore, the main flow which is in proportion to the pilot flow by a ratio of the cross-sectional area of the orifice 237 to the cross sectional area of the orifice 228, flows into the actuator from the annular groove 208 through the port 225 of the supply spool 214, its interior passage 226, the lower chamber 216, the orifice 237, and the output port 231. Conversely, the similar main return flow flows from the actuator to the reservoir through the other output port 231, the orifice 237, the lower chamber 216, the interior passage 226, the port 225 of the discharge spool 214 and the annular groove 209. The main return flow is also in proportion to the pilot return flow by a ratio of the cross-sectional area of the orifice 237 to the cross-sectional area of the orifice 228 in the pilot return flow path.

Since the relief valve assembly and the flow control valve assembly 470 (See FIGS. 38, 39 and 40) are stacked upon the control valve 201 as described hereinabove, the pilot flow which flows in response to the switching operation of the solenoid valve 500 from the hydraulic pressure source through the input port 212, the passage 244, the annular groove 208, the passage 245 and the pilot input port 252 in the control valve 201, the input ports 472 and 472' of the valve assemblies 470, the solenoid valve 500, and the outlet ports 474 and 474', is controlled by the control valve assembly 470, that is one of the control valve units 476' to a predetermined rate. Therefore, the pressure drop across the orifice 228 is in proportion to the flow rate controlled by the control valve assembly 470, so that the spool 214 is so moved as to produce the main flow whose volumetric flow is in proportion to that of the pilot flow by a predetermined amplification factor or ratio of the cross-sectional area of the orifice 237 to that of the orifice 228. Thus the control valve 201 functions as a flow control valve.

If a load in excess of a predetermined level is exerted upon the actuator when the latter is locked by switching the solenoid to the neutral position, the excess load pressure is transmitted from the actuator to the relief valve 476 in the valve assembly 470 through the path consisting of one of the output ports 231, the passages 232 and 207, the orifice 228 and the pilot port 227 of the control valve 201, and the input ports 474 and 474' of the valve assemblies 470. The liquid under excess pressure forces through the relief valve 476 and flows through the discharge ports 473 and 473', a check valve 477 which also functions as a main relief valve, the other outlet ports 474 and 474', the passage 232, the orifice 228, the passages 208 and 232 and the output port 231 into the opposite side of the actuator. The above pilot flow rate is detected by the orifice 228 in terms of a pressure drop thereacross. Therefore, the one spool 214 is moved upwardly whereas the other spool 214 is moved downwardly, so that the liquid under pressure may be supplied from the annular groove 208 to the negative pressure side of the actuator whereas the liquid under pressure on the positive side of the actuator is returned to the reservoir through the annular groove 209. Thus the control valve 201 in accordance with the present invention functions as an overload relief valve. It will be understood that the control valve 201 in accordance with the present may function as a throttle valve, sequence valve or load check valve when a suitable valve assembly 470 is mounted on the control valve 201 and that the control valve 201, may handle a large capacity of high-pressure liquid in response to the output signal or pilot flow from the small — capacity pilot valve mounted upon the control valve 201.

In the above embodiment, only one control valve 201 is used, it will be understood that a plurality of control valves 201 may be used in tandem as will be described hereinafter with reference to FIGS. 42 and 43. The control valves 201 used in tandem must be modified a little. That is, as indicated by the chain lines in FIGS. 24, 28 and 29 lateral communication ports 210 and 212 (see FIGS. 28 and 29) are bored in order to intercommunicate between the annular grooves 208 and 209, respectively, of the adjacent control valves 201 and 201a. Furthermore, the bottom cover or the subplate 204 must be so modified as to be provided with only a pair of output ports 231. The valve proper 202 must be provided with through bolt holes (see FIG. 24) 264 for joining the control valves 201 and 201a in tandem with through bolts 265. (see FIG. 42).

In the embodiment shown in FIGS. 42 and 43, the control valve 201a is provided with the modified bottom plate 204a and two control valves 201 and 201a are intercommunicated through the communication ports 210 and 211.

The hydraulic control valve systems described hereinbefore may be used without adding any hydraulic component part when a hydraulic pressure source, such as a hydraulic pump is provided with a main relief valve and an unloading valve, but if the hydraulic power source is not provided with them, a control valve system which functions as a main relief valve and an unloading valve must be provided as will be described hereinafter with reference to FIGS. 44-47.

A control valve 301 shown in FIGS. 44-47 generally comprises a valve proper 302, and top and bottom covers 303 and 304 which securely joined to the valve

proper 302 with through bolts 305. The valve proper 302 is provided with a valve cylinder or bore 306 and a vertical passage 307 bored through the valve proper 302 in parallel with the valve bore 306. A spool 314 having a port 325 formed through the side wall thereof is slidably fitted into the valve bore 306 and is normally held in the lowermost position under the force of a spring 323 loaded between the undersurface of the top cover 303 and the upper surface of a partition wall 315 of the spool 314, so that the port 325 is interrupted from communicating with an annular groove 309 formed around the valve bore 306. However, when the spool 314 is moved upwardly, the port 325 opens to the annular groove 309 in a manner substantially similar to that described hereinbefore. As shown in FIG. 47 the annular groove 309 is communicated with a discharge port 313 of the bottom cover 204 through a communication passage 346 drilled into the valve proper 302, and as shown in FIG. 44 the annular groove 309 is also communicated with a discharge port 313 of the top cover 303 through a communication passage 347 in the valve proper 302. The lower chamber 316 or interior passage 326 of the spool 314 is communicated with an inlet port 312 of the bottom cover 304 through an orifice 337. A lateral communication passage 332 is formed in the bottom cover 304 in order to intercommunicate between the lower end of the vertical passage 307 in the valve proper 302 and the inlet port 312 of the bottom cover 304. A pilot port 352 which opens at the upper surface 351 of the top cover 303, is communicated with the vertical passage 307 in the valve proper 302 through a lateral communication passage 329 and an orifice 328 screwed into the top cover 303 between the communication passage 329 and the vertical passage 307. The passage 329 in the top cover 303 is further communicated with an upper chamber 318 defined above the partition wall 315 in the valve bore 306 through a damping orifice 330.

A relief valve assembly 470 (of the type described with reference to FIG. 38) is mounted on the control valve 301 and a solenoid valve 500 is further mounted on the relief valve assembly 470, and they are securely joined together with through bolts or the like. The inlet port 312 is connected to the hydraulic pressure source whereas the discharge port 313 is connected to the reservoir.

When the solenoid valve 500 is so energized as to intercommunicate the inlet and discharge ports of the valve assembly 470, the pilot flow flows from the hydraulic pressure source through the inlet port 312, the communication passages 332, 307, the orifice 328 and the pilot inlet port 352 in the valve proper 302, the inlet port of the valve assembly 470, the solenoid valve 500, the discharge port of the valve assembly 470, the pilot discharge port 353, the communication passage 347, the annular groove 309, the communication passage 346, and the discharge port 313 of the valve proper 302 to the reservoir. In response to the pressure difference across the orifice 328 in the pilot flow path, the spool 314 is moved upwardly so that the port 325 opens to the annular groove 309. Therefore, the high-pressure liquid flows from the hydraulic pressure source through the inlet port 312, the orifice 337, the lower chamber 316, the interior passage 326 in the spool 314, the bore 325, the annular groove 309, the communication passage 346, and the discharge port 313 to the reservoir.

Thus the control valve 301 functions as an unloading valve.

Next in operation the solenoid valve 500 is so energized as to interrupt the communication between the inlet and discharge ports of the valve assembly 470. Therefore the relief valve in the valve assembly 470 is opened in response to the abnormal pressure rise in the hydraulic pressure source so that the pilot flow flows from the inlet port 312 through the orifice 328, and the relief valve in the valve assembly 470 to the reservoir. As a result the spool 314 is caused to move upwardly, so that the main flow flows from the inlet port 312 through the port 325 to the reservoir. Thus the control valve 301 functions as a main relief valve. Since the flow rate or volumetric flow control is not required when the control valve 301 is used as an unloading valve and a main relief valve, the cross-sectional area of the orifice 337 may be increased as large as possible, or the orifice 337 may be eliminated.

The control valves 301 of the type described above may be used in tandem. In this case the bottom cover 304 must be modified so as to provide a bottom cover 304a shown in FIG. 48. The bottom cover 304a is provided with a blind inlet port 312a which opens only to the valve proper 302. Furthermore, the valve proper 302 must be so modified as to be provided with communication ports 310 and 311 for opening the blind supply port 312a of the bottom cover 304a and the annular groove 309 in the valve proper 302 at the side wall thereof, as indicated by the chain lines in FIG. 44. In addition the control valve proper 302 must be provided with through bolt holes 364 (see FIG. 44) in order to pin the control valve 301a of the type described above in tandem with the control valve 201 of the type shown in FIGS. 42 and 43. The communication ports 210 and 310 are joined together the communication ports 211 and 311 are also joined together, and the control valves 301a and 201 are joined in tandem via the through bolts 365 as shown in FIGS. 49 and 50.

Next referring FIGS. 51-56, a variation of the control valve 301 which may function as a carry-over valve will be described.

The modified control valve 301 is substantially similar in construction to the control valve described in detail with reference to FIG. 44 except that another annular groove 309a is formed around the valve bore 306 and is communicated through a communication passage 347a formed in the valve proper 302, and a lateral communication passage 336 formed in the top cover 303, with a pilot port 367 opening at the mounting seat 351 thereof, and that the annular groove 309a is communicated with a carry-over port 313a which opens at the side wall of the valve proper 302.

When the pilot inlet port 352 is communicated with the pilot port 367 by the solenoid valve 500 mounted upon the control valve 301, the pilot flow flows from the hydraulic pressure source to the reservoir through the inlet port 312, the lateral passage 332, the vertical passage 307, the orifice 328, the lateral passage 329, the pilot outlet port 352, the inlet port of the valve assembly 470, the solenoid valve 500, the outlet port of the valve assembly 470, the pilot port 367, the lateral passage 366, the communication passage 347a, the annular groove 309a and the carry-over port 313a. The pilot flow flows from the carry-over port 313a into a hydraulic circuit (not shown). In response to the pressure drop across the orifice 328 in the pilot flow path,

the spool 314 is moved upwardly so that the port 325a is first opened to the annular groove 309a before the port 325 opens to the annular groove 309. Therefore, the main flow flows from the inlet port 312 through the port 325a of the spool 314, the annular groove 309a where the main flow joins the pilot flow, and the carry-over port 313a.

Thus the control valve 301 or 301a functions as a carry-over valve.

Furthermore, according to the present invention a plurality of control valves 201a and 301a may be joined in tandem as will be described hereinafter with reference to FIGS. 57 and 58. In the control valve 301a used in this embodiment the blind inlet port 312a in the bottom cover 304a is opened at the undersurface thereof, and the communication ports 310 and 311 are connected to the communication ports 210 and 211 of the adjacent control valve 201a. Similarly, three control valves 201a are joined through the communication ports 210 and 211. The communication port 211 of the rightmost control valve 201a is opened at the side wall thereof, whereas the carry-over port 313a is opened at the side wall of the control valve 301a. These control valves 301a and 201a are joined together with through bolts 365.

In addition to the various fundamental embodiments of the present invention described hereinbefore, various modifications can be effected with or without valve assemblies. In a modification shown in FIGS. 59 and 60, the solenoid valve 500 is replaced by the conventional multicontrol valves and linear control valves. In the instant modification connecting plates 670 and 670a shown in FIGS. 61 and 62 are used, as will be described in more detail hereinafter.

Referring first to FIG. 61 illustrating the connecting plate 670, it comprises a connecting plate proper 671 provided with through holes 672 in alignment with the pilot ports 227 of the top cover 203 of the control valve 201 or 201a and with the output ports 474 or 474' of the valve assembly 470, and bolt holes 673 in alignment with the tapped holes 254 and the bolt holes 475 or 475'.

Referring to FIG. 62, the connecting plate 670a comprises a connecting plate proper 671a provided with through holes 672a, 673a and 674a in alignment with the pilot inlet port 352, the discharge port 353 and the pilot port 352 of the top cover 303 of the control valve 301 or 301a or the inlet port 472 or 472', the discharge port 473 or 473' and the output port 474 or 474' of the valve assembly 470, respectively, and through bolt holes 657a in alignment of the tapped holes 354 or the through bolt holes 475 or 475' of the valve assembly.

The multicontrol valve and linear control valve may be connected to the valve assemblies or control valves 201 or 201a and 301 or 301a through the connecting plates 670 held in place upon the mounting seats of the valve assemblies or control valves, and connecting lines extending from the through holes 672, 672a, and 673a. The through hole 674a in the connecting plate 670a may be used as a pilot carry-over port. Thus the control valves 201, 201a, 301 and 301a in accordance with the present invention may be controlled by the multicontrol valves and linear control valves. Since the linear control valve controls the flow rate of the liquid under pressure, the pilot flow rate may be controlled in response to the operation of the linear control valve while the cross-sectional areas of the orifices 228 and 328 are

maintained constant, and in response to the pressure drop across the orifice 228 or 328 the main flow may be suitably controlled.

FIG. 63 illustrates another modification in which the control valve 201a in accordance with the present invention is used together with the valve assemblies and a conventional solenoid servo valve 500a. The top 203a of the control valve 201a is provided with another pair of pilot ports and pilot passages 229a which are communicated with the upper chambers 217 through damping orifices (not shown), but are not communicated with the orifices 228 and hence to the outlet ports 231 (compare with FIG. 21).

The pilot flow flowing into a port P of the solenoid valve 500a, which is adapted to change the degree of opening in response to the electrical signal applied thereto, from the pilot port 252 of the control valve 201a through the ports 472, 472', and so on of the valve assemblies 470 is made to pass by the solenoid valve 500a which is switched to the left position, through a port A, a passage 501a, a variable-cross-section orifice 502a, a port A', a pipe line 503a, the passage 229a', the orifice 228, the passage 207 and via the passage 232 in the bottom cover 204 to the output port 231. The pressure of the above pilot flow immediately before the orifice 502a is transmitted to the upper chamber 217 in the control valve 201a through the port A, a passage 504a, the outlet ports 474, 474' and so on of the valve assemblies 470 and the passage 229a. The pressure at the output port 231 is transmitted to the lower chamber 216 through the orifice 237. As a result, the spool 214 is caused to move downwardly so that the main flow flows from the annular groove 208 through the port 225 of the spool 214 to the output port 231.

The pilot return flow flows from the right output port 231, the passages 232 and 207, the orifice 228, the pilot passage 229a', pipe line 503a, a port B', a variable-cross-sectional orifice 502a, a passage 501a, the port B, a port R, the discharge ports 473, 473' and so on of the valve assemblies 470, the discharge port 263, and via the annular groove 209 to the reservoir. In this case, in response to the pressure drop across the orifice 502a in the solenoid valve 500a, the right spool 214 is caused to move upwardly so that the main flow flows from the output port 231 through the port 225 of the right spool 214 and the annular groove 209 to the reservoir.

Therefore it is readily seen that the amplification factor or ratio of the main flow to the pilot flow may be arbitrarily varied by changing the cross-sectional area of the orifice 502a in the solenoid valve 500a. Thus the control valve function as a servo valve. In the instant modification the orifices 228 in the pilot passages 229a' may be eliminated, but when an overload relief valve assembly 470 is mounted, the orifices 228 are required for setting the minimum sensitivity.

As described above, according to the present invention when a small-capacity pilot valve or valves capable of various functions are mounted on control valves and the solenoid valves are mounted on the valve assemblies, or other suitable control valves such as a linear control valve and multicontrol valve are connected through the connecting plates to the control valves or valve assemblies, the control valve or valves in accordance with the present invention may accomplish the various functions of the pilot valves and the control valves with a large capacity of liquid under pressure. If

required, the control valve in accordance with the present invention may function as a servo valve, a main relief-unloading valve or a carry-over valve. Furthermore, the control valves in accordance with the present invention may be joined in tandem so as to provide a power unit. Thus there has been provided a control valve for versatile functions which may be readily standardized and which may make the hydraulic equipment or system in construction and light in weight.

So far only the essential features of the present invention have been described with reference to the preferred embodiments thereof, but it will be understood that various modifications and variations can be affected within the scope of the present invention as described above in the specification and defined in the appended claims.

What is claimed is:

1. A hydraulic control valve, comprising a valve body having an elongated chamber, a main flow input port and a main flow output port which both communicate with said chamber; a valve spool having a hollow interior which communicates with said chamber at one axial end of said spool, and a circumferential wall provided with an opening which communicates with said hollow interior, said spool being axially slidable in said chamber between a normal position in which said opening is out of communication with both of said ports, and two operated positions in each of which said opening is in communication with a respective one of said ports; an external port formed in said valve body and communicating with said chamber adjacent said one axial end of said spool; a pilot flow passage in said valve body, bypassing said chamber and having one open end communicating with the exterior of said valve body and another open end communicating with said external port; orifice means interposed in said pilot flow passage intermediate said one end and said other end thereof; and aperture means communicating with said chamber adjacent the other end of said valve spool, and with said pilot flow passage intermediate said orifice means and said one end, so that a pressure difference which develops in said pilot flow passage across said orifice means acts upon said ends of said valve spool.

2. A control valve as defined in claim 1, wherein said input and output ports are used as common input and output ports; and further comprising an additional valve spool, pilot flow passage, orifice means and external port similar to the previously mentioned ones and also disposed in said control valve, whereby a pair of control valve units are incorporated in said control valve.

3. A control valve as defined in claim 2, further comprising additional orifice means interposed between said input and output ports.

4. A control valve as defined in claim 3, wherein some or all of said orifice means may have their cross-sectional areas varied by operation from the exterior of said control valve.

5. A control valve comprising a valve body; an internal passage in said valve body and having opposite end portions;

an external input port and an external output port formed in said valve body and each communicating with said internal passage;

a pilot port formed in said valve body and communicating with said passage;

spool means having opposite axial ends and being shiftable in said internal passage intermediate said end portions between a normal position in which it prevents communication between said external ports, and two operated positions in which it communicates a respective one of said external ports with said pilot port;

a pilot flow passage formed in said valve body and bypassing said internal passage and said spool means, said pilot flow passage communicating with said opposite end portions adjacent said opposite axial ends of said spool means, said pilot flow passage having an inlet for a pilot flow at the exterior of said valve body;

and orifice means interposed in said pilot flow passage so that a pressure difference may develop across said orifice means and is transmitted to said opposite axial ends of said spool means.

6. A hydraulic control valve, comprising a valve body having a cylindrical valve chamber; port means communicating with said valve chamber and defining two paths for a main fluid flow which pass through said valve chamber and through one end thereof;

a hollow valve spool received in said valve chamber and slidable therein between positions in which it completes and interrupts said main fluid flow paths;

a passage defining a pilot fluid flow path which bypasses said valve chamber;

restricted orifice means interposed in said pilot fluid flow path;

restricted orifice means in said main fluid flow paths located at said one end of said valve chamber; and conduit means for joining the fluid flow of said pilot fluid flow and the fluid flow of said main fluid flow adjacent said restricted orifice means for said main fluid flow paths, for controlling the displacement of said valve spool and the volumetric flow of fluid in the main fluid flow paths as a function of the difference between the pressure drops which occur in the fluid flows across said restricted orifice means.

7. A hydraulic control valve, comprising a valve body having a cylindrical valve chamber; ports means communicating with said valve chamber and defining two paths for a main fluid flow which pass alternately in opposite directions through said valve chamber and through one end thereof;

a hollow valve spool received in said valve chamber and slidable therein between positions in which it completes and interrupts said main fluid flow paths;

a passage defining a pilot fluid flow path which bypasses said valve chamber;

restricted orifice means interposed in said pilot fluid flow path;

restricted orifice means in said main fluid flow paths located at said one end of said valve chamber; and conduit means for joining the fluid flow of said pilot fluid flow and the fluid flow of said main fluid flow adjacent said restricted orifice means for said main fluid flow paths, for controlling the displacement of

said valve spool and the volumetric flow of fluid in the main fluid flow paths as a function of the difference between the pressure drops which occur in the fluid flows across said restricted orifice means.

8. A hydraulic control valve, comprising a valve body having a cylindrical valve chamber; port means communicating with said valve chamber and defining a main fluid flow path which passes through said valve chamber and through one end thereof;

a hollow valve spool received in said valve chamber and slidable therein between positions in which it completes and interrupts said main fluid flow path; passage means in said valve body, bypassing said valve chamber and defining a pilot flow path which communicates with said main flow path in the region of said one end of said valve chamber;

a first restricted orifice in said main flow path at said one end of said valve chamber, intermediate the latter and said pilot flow path;

a second, damper orifice communicating the other end of said valve chamber with said pilot flow passage; and

a third orifice in said pilot flow path intermediate said damper orifice and said main flow path.

9. A hydraulic control valve, comprising a valve body having a cylindrical valve chamber; port means including a first and a second exterior port, and a third port which communicates with said valve chamber, said first and second ports defining a first path for a first main fluid flow, and said first and third ports defining a second path for a main fluid flow which passes through said valve chamber and through one end thereof;

a hollow valve spool received in said valve chamber and slidable therein between positions in which it completes and interrupts said second main fluid flow path;

a passage defining a pilot fluid flow path which bypasses said valve chamber;

first restricted orifice means interposed in said pilot fluid flow path;

second restricted orifice means in said second main fluid flow path located at said one end of said valve chamber; and

conduit means for joining the fluid flow of said pilot fluid flow and the fluid flows of both of said main fluid flows adjacent said second restricted orifice means, for controlling the displacement of said valve spool and the volumetric flow of fluid in the main fluid flow paths as a function of the difference between the pressure drops which occur in the fluid flows across said restricted orifice means.

10. A hydraulic control valve, comprising a valve body having a cylindrical valve chamber; port means including a first and a second port which communicate with one another to form a first main fluid flow path, a third and fourth port both communicating via said valve chamber with said first port and defining second and third main fluid flow paths which pass through said valve chamber and through one end thereof;

a hollow valve spool received in said valve chamber and having a pair of axially spaced apertures in its circumference, said valve spool being slidable in said valve chamber between a position in which communication between said apertures and said

third and fourth ports is interrupted, a position in which one of said apertures communicates with said third port, and a position in which the other of said apertures communicates with said fourth port; a passage defining a pilot fluid flow path which bypasses said valve chamber; 5 first restricted orifice means interposed in said pilot fluid flow path; second restricted orifice means in said second and third main fluid flow paths located at said one end of said valve chamber; and conduit means for joining the fluid flow of said pilot fluid flow and the fluid flows of all of said main fluid flows adjacent said restricted orifice means for said second and third main fluid flow paths, for controlling the the displacement of said valve spool and the volumetric flow of fluid in the main fluid flow paths as a function of the difference between the pressure drops which occur in the fluid flows across said restricted orifice means. 10 15 20

11. A hydraulic control valve, comprising
a valve body having a cylindrical valve chamber; a single port communicating with said valve chamber and defining a path for a main fluid flow which passes through said valve chamber and through one end thereof; 25 a hollow valve spool received in said valve chamber and having a circumferential wall formed with an opening, said valve spool being slidable in said valve chamber between a position in which said opening communicates with said port, and another position in which said opening is out of communication with said port; biasing means biasing said valve spool to said other position; 30 a passage defining a pilot fluid flow path which bypasses said valve chamber; restricted orifice means interposed in said pilot fluid flow path; restricted orifice means in said main fluid flow path 40 located at said one end of said valve chamber; and conduit means for joining the fluid flow of said pilot fluid flow and the fluid flow of said main fluid flow adjacent said restricted orifice means for said main fluid flow path, for controlling the displacement of said valve spool against the force of said biasing means and the volumetric flow of fluid in the main fluid flow path as a function of the difference between the pressure drops which occur in the fluid flow across said restricted orifice means. 45 50

12. A hydraulic control valve, comprising
a valve body having a cylindrical valve chamber; port means including a pair of axially spaced ports

communicating with said valve chamber and defining two paths for main fluid flows which pass through said valve chamber and through one end thereof; a hollow valve spool received in said valve chamber and having a circumferential wall formed with a pair of axially spaced openings, said valve spool being slidable in said valve chamber between a position in which said openings are both out of communication with said ports, and positions in which respective ones of said openings communicate with the respective ports; a passage defining a pilot fluid flow path which bypasses said valve chamber but communicates with one of said ports; restricted orifice means interposed in said pilot fluid flow path; restricted orifice means in said main fluid flow path located at said one end of said valve chamber; and conduit means for joining the fluid flow of said pilot fluid flow and the fluid flows of said main fluid flows adjacent said restricted orifice means for said main fluid flow paths, for controlling the displacement of said valve spool and the volumetric flow of fluid in the main fluid flow paths as a function of the difference between the pressure drops which occur in the fluid flows across said restricted orifice means. 20 25 30 35

13. A hydraulic control valve, comprising
a valve body having a cylindrical valve chamber; port means communicating with said valve chamber and defining a path for a main fluid flow which passes through said valve chamber and through one end thereof; a hollow valve spool received in said valve chamber and slidable therein between positions in which it completes and interrupts said main fluid flow path; a passage defining a pilot fluid flow path which bypasses said valve chamber; restricted orifice means interposed in said pilot fluid flow path; restricted orifice means in said main fluid flow path located at said one end of said valve chamber; and conduit means for joining the fluid flow of said pilot fluid flow and the fluid flow of said main fluid flow adjacent said restricted orifice means for said main fluid flow path, for controlling the displacement of said valve spool and the volumetric flow of fluid in the main fluid flow path as a function of the difference between the pressure drops which occur in the fluid flows across said restricted orifice means. 40 45 50
